UNITED STATES PATENT OFFICE.

WILLIAM F. RAY, OF CHICAGO, ILLINOIS.

VULCANIZER.

1,296,215.

Specification of Letters Patent. Patented Mar. 4, 1919.

Application filed October 2, 1918. Serial No. 256,571.

To all whom it may concern:

Be it known that I, WILLIAM F. RAY, a citizen of the United States, residing at Chicago, in the county of Cook and State of Illinois, have invented a new and useful Improvement in Vulcanizers, of which the following is a specification.

This invention relates particularly to vulcanizers employing steam as a means of vulcanizing rubber products, such as automobile tires, interliners, inner tubes, etc.

The primary object is to provide a vulcanizer adapted to produce a uniform "cure" of the rubber article undergoing treatment. It is particularly important, for instance, that in the manufacture of rubber tires, interliners, tubes, etc., the articles shall be thoroughly and uniformly cured, and shall not be overcured at any point. Where an overcure occurs, the resiliency and flexibility is impaired, and the life of the tire, for example, is greatly shortened.

The invention is illustrated in its preferred embodiment in the accompanying drawing, in which—

Figure 1 represents an end view of a cylindrical vulcanizer embodying the invention, the door being swung open and the interior of the vulcanizer appearing in perspective; and Fig. 2, a broken sectional view taken as indicated at line 2 of Fig. 1.

In the construction illustrated, A represents the cylindrical body of the vulcanizer; A¹, the door which serves to close the front end of the vulcanizer; B, B¹, a pair of steam injecting devices for introducing steam into the vulcanizer; and C, a longitudinal track in the lower portion of the vulcanizer, adapted to enable a small truck, carrying a standard or standards, for supporting the articles, to be run into the vulcanizer.

The body of the vulcanizer may conveniently be of a diameter of about six feet and of a length of about fifteen to twenty feet. The dimensions may vary, of course, according to the capacity desired. The door A¹ is supported on a vertical pivot A², and may be closed and secured in the usual manner.

The steam injectors B and B¹ are so constructed and disposed as to produce circumferential currents of steam adjacent the inner cylindrical surface of the vulcanizer, alternate currents preferably passing in one direction, and the remaining alternate cur-

rents in the opposite direction, as indicated by the arrows in the lower portion of Fig. 1.

To this end, the steam injecting device B comprises a main pipe 1 which extends through the upper wall of the cylinder some 60 distance back of its front end; longitudinal branches 2 and 3 disposed adjacent the upper portion of the inner surface of the cylinder A and connected with the pipe 1 by a T-fitting; and curved discharge pipes 4 and 5 connected by suitable fittings with the ends of the branch pipes 2 and 3 and extending in opposite directions circumferentially adjacent the inner surface of the cylinder and having, respectively, discharge orifices 6 and 7 at the lower portion of the cylinder, the extremities of the curved pipes projecting past each other, as indicated at the lower portion of Fig. 1.

Similarly, the steam injector B¹ has a 75 main pipe extending through the upper wall of the cylinder some distance back of the injector B and equipped inside the cylinder with longitudinal branch pipes 2^a and 3^a, from which extend the circumferential discharge pipes 4^a and 5^a, which have their discharge orifices, respectively, at the points 6^a and 7^a.

The discharged portions of the curved pipes extend below the rails of the track C. 85

From the description given, it will be understood that a plurality of steam discharge orifices are provided, so disposed as to produce circular currents of steam adjacent the inner cylindrical wall of the vulcanizer. 90 Alternate currents, in the arrangement illustrated, pass in one direction, and the other alternate currents pass in the other direction, so that adjacent currents are moving in opposite directions, but not directly opposed to each other, that is, as will be understood from Fig. 1, the orifices are staggered with relation to each other. The result is to produce circulating currents of steam adjacent the inner surface of the vulcanizer body. Thus, there is produced an envelop of live steam adjacent the inner cylindrical wall of the vulcanizer; and, as there is more or less frictional engagement and meeting of the currents, the result is to 100 produce a substantially uniform diffusion of the live steam in an envelop immediately inside of the cylindrical wall of the vulcanizer. From this envelop the steam diffuses and fills the interior of the vulcanizer, so 110

that a series of interliners, for illustration, supported on a longitudinal pipe carried by standards mounted on a truck on the track C will, in the operation of the vulcanizer, be subjected to a substantially uniform curing action, without danger of overvulcanizing at any point. It will be understood that in curing tires or interliners, which are of circular form, the articles are so supported on the truck or carriage as to lie in planes parallel with the ends of the vulcanizer and occupy the central space of the vulcanizer, that is, the space inside of the imaginary cylinder containing the pipes 5 and 5^a. Any heat radiated directly from the pipes 5 and 5^a, is, of course, substantially uniformly diffused in the envelop of steam created by the circulating currents.

The foregoing detailed description has been given for clearness of understanding only and no unnecessary limitation should be understood therefrom, but the appended claims should be construed as broadly as permissible in view of the prior art.

25. What I regard as new and desire to secure by Letters Patent is:

1. In a vulcanizer, the combination with a vulcanizer body, of steam-injecting means comprising a plurality of discharge orifices 30 opening in a circumferential direction adjacent the inner surface of the wall of said vulcanizer body and adapted to produce circumferentially circulating steam-currents within the body of the vulcanizer.

35. 2. In a vulcanizer, the combination with a vulcanizer body, of steam-injecting means comprising curved pipes forming an annular arrangement and having a plurality of discharge orifices disposed in different transverse planes.

40. 3. In a vulcanizer, the combination of a cylindrical body, and steam-injecting means

comprising a pipe equipped with longitudinal branches and curved discharge pipes extending from said branches circumferentially within the cylinder.

45. 4. In a vulcanizer, the combination of a cylindrical body, and steam-injecting means comprising a pipe equipped with longitudinal branches and curved discharge pipes extending from said branches in opposite directions circumferentially within the cylinder.

50. 5. In a vulcanizer, the combination of a cylindrical body, and means for injecting steam into said body comprising a plurality 55 of circumferential pipes adjacent the inner surface of the cylindrical body, some of said pipes having discharge orifices opening in one direction, and other of said pipes having discharge orifices opening in the opposite 60 direction.

55. 6. In a vulcanizer, the combination of a cylindrical body, and steam-injecting means comprising a series of curved pipes forming an annulus, said pipes having overlapping 65 ends in staggered relation, the orifices of alternate pipes opening in one direction and the orifices of the other alternate pipes opening in the opposite direction.

70. 7. In a vulcanizer, the combination of a cylindrical body, and a plurality of steam-injecting devices, each of said devices comprising a main pipe and longitudinal branches extending from said pipe within the upper portion of the cylindrical body, 75 said branches of each injecting device being equipped with curved discharge pipes extending in opposite directions circumferentially within the cylindrical body and having discharge orifices disposed in staggered relation at the lower portion of the cylindrical body.

WILLIAM F. RAY.
